(57) **CLAIM**

The ornamental design for a cushion for furniture leg, as shown and described.

DESCRIPTION

FIG. 1 is a top, side perspective view of a cushion for furniture leg;

FIG. 2 is a top plan view of a cushion for furniture leg;

FIG. 3 is a bottom plan view of a cushion for furniture leg;

FIG. 4 is a side elevation view of a cushion for furniture leg;

FIG. 5 is a side elevation view of a cushion for furniture leg;

FIG. 6 is a cross-sectional view of a cushion for furniture leg, taken along the lines 6-6 shown in FIG. 4; and,

FIG. 7 is a cross-sectional view of a cushion for furniture leg, taken along the lines 6-6 shown in FIG. 4, shown with environment.

The broken line showing of a furniture leg is for the purpose of illustrating environmental structure and forms no part of the claimed design.

1 Claim, 4 Drawing Sheets
